UNITED STATES PATENT OFFICE.

WILLIAM J. KEEP, OF DETROIT, MICHIGAN, ASSIGNOR TO THE MICHIGAN STOVE COMPANY, OF DETROIT, MICHIGAN, A CORPORATION OF MICHIGAN.

ELECTRIC COOKING-RANGE.

1,157,111.

Specification of Letters Patent. Patented Oct. 19, 1915.

Application filed December 26, 1914. Serial No. 879,215.

To all whom it may concern:

Be it known that I, WILLIAM J. KEEP, a citizen of the United States of America, residing at Detroit, in the county of Wayne and State of Michigan, have invented certain new and useful Improvements in Electric Cooking-Ranges, of which the following is a specification, reference being had therein to the accompanying drawings.

10 This invention relates to the art of electric cooking ranges and has special reference to improvements in the construction of such ranges, whereby the same shall possess, to the highest degree attainable, safeguards

15 precluding short circuits, heating element insuring expeditious cooking with a minimum expenditure of current, and indicating devices that simplify the use of the range.

A further object of this invention is to 20 provide a range structure embodying a cooking top, a main oven, a broiler, and a warming oven, all constructed and assembled upon a profitable manufacturing basis that insures a maximum heat efficiency in the preparation of food. The cooking top, ovens and broiler include armored heating elements of novel design and construction, and associated with these elements is a terminal box and indicating devices having individual 25 characteristics that will hereinafter appear as the nature of the range is better understood.

The essential features of the range, as 30 enumerated above, will be hereinafter specifically described and then claimed, and reference will now be had to the drawings showing a practical embodiment of the invention, wherein—

Figure 1 is a plan of the electric cooking 35 range showing the heating element of the warming oven in dotted lines; Fig. 2 is a front elevation of the range illustrating controlling and indicating devices thereof; Fig. 3 is a horizontal sectional view of the main oven of the range, taken on or about the line 40 III—III of Fig. 2; Fig. 4 is a longitudinal sectional view of the oven, taken on or about the line IV—IV of Fig. 1; Fig. 5 is a transverse sectional view of the same, taken on or

about the line V—V of Fig. 1; Fig. 6 is a 50 plan of the terminal box and conduits thereof; Fig. 7 is a front elevation of the same showing its position relative to the cooking top of the range; Fig. 8 is a longitudinal sectional view of the terminal box; Fig. 9 55 is an enlarged detail of a portion of the same, showing one of the combined switches and indicating devices; Fig. 10 is a front elevation of the same; Fig. 11 is a plan of a 60 cooking top heating element, partly broken away; Fig. 12 is a front elevation of the same, partly broken away and partly in section; Fig. 13 is a cross sectional view of the heating element taken on the line XIII—XIII of Fig. 11; Fig. 14 is a sectional view 65 taken on or about the line XIV—XIV of Fig. 11; Fig. 15 is a perspective view of an end of a heating unit adapted to form part of the heating element; Fig. 16 is a 70 plan of the heating element especially designed for the main oven and broiler, showing the same partly broken away; Fig. 17 is a front elevation of the same, partly broken away and partly in section; Fig. 18 is a cross sectional view of the same taken 75 on the line XVIII—XVIII of Fig. 16; Fig. 19 is an enlarged sectional view taken on the line XIX—XIX of Fig. 16; Fig. 20, is an enlarged cross sectional view taken on the line XX—XX of Fig. 16; Fig. 21, is a plan 80 of an end of a heating unit of the heating element, and Fig. 22 is a diagrammatic view of the wiring or electrical connection of the various heating elements, controlling and indicating devices.

85 In describing the invention by aid of the views above referred to, I desire to point out that I intend the same as merely illustrative of an example whereby my invention may be applied in practice, and I do not care to 90 confine myself to the precise construction and arrangement of parts shown. The following description is therefore to be broadly construed as including substitute constructions and arrangements of parts which are 95 the obvious equivalents of those to be hereinafter referred to.

Considering Figs. 1 to 8 inclusive, the elec-

tric cooking range comprises an oblong horizontally disposed casing having a bottom plate 1, end walls 2 and 3, a rear wall 4, a front wall 5, and a top plate 6, said plate 5 closing approximately one half the casing at an end thereof and constituting a "cooking top." At the opposite end of the casing, the end wall 3 and the rear wall 4 are provided with vertical extensions 7 and 8 co-operating with a transverse wall 9, a top plate 10, a horizontal partition 11 and a front wall 12 in forming an oven housing, which is superimposed relative to the range casing. The oven housing accommodates the main oven, to be hereinafter referred to, and the range casing has a hinged transverse partition 13 dividing the casing into two compartments, the compartment beneath the oven housing serving as a warming oven.

20 The range casing is supported by suitable legs 14, and the top plate 6 of said casing has a rectangular opening 15, and depending ledges 16 and 17 at the edges of said opening. The ledge 16 accommodates the depending flanges of a grid plate 18 having rectangular openings 19. Below the openings 19 are drip pans 20 removably held by cleats 21 connected to the bottom side of the ledge 17 and to a transverse terminal member 22, that is in a horizontal plane with the ledge 17 and co-operates therewith in supporting heating elements for the cooking top. A heating element is located in each of the openings 19 of the grid plate 18 and the heating surface of each element is slightly above the top surface of the grid plate 18 whereby a utensil can be easily placed upon the heating element.

Reference will now be had to Figs. 11 to 40 15 inclusive showing one of the heating elements of the cooking top, and in constructing and designing the elements I have aimed to provide a unitary structure that can be bodily removed from the top plate should 45 occasion so require and in designing the element the exposed surfaces thereof have been given such shape as to deflect or shed grease, liquid and foreign matter which may be deposited upon the same. The various 50 units of the element are armored and provision is made to eliminate buckling and to compensate for expansion and contraction without disturbing terminals of the units or impairing electrical connections thereof.

55 The heating element comprises a rectangular frame having front and rear rails 55 connected by side bars 23 and supports 24 and 25. The upper faces of the side bars 23 are convex and provided with spaced apertured bosses 26. The apertures 27 of said bosses are in communication with pockets 28 in the under sides of the bars 23 and mounted in the apertures 27 are metallic eyelets 29 having smooth bores. The eyelets 29 are insulated from the side bars 23 by

mica washers 30 and 31 at the flanged ends of the eyelets. The mica washers 31 rest upon the bosses 26 and the pockets 28 house the mica washers 30 and small metallic washers 32 employed to prevent the washers 30 from being injured when the ends of the eyelets are upset or flanged. 70

Loosely mounted in the eyelets 29 are the threaded shanks 33 of terminals 34. The terminals are in the form of screws having 75 nuts 35 adjacent the heads thereof, that rest upon the upper ends of the eyelets 29. The nuts 35 coöperate with washers 36 in retaining bridge pieces 37, terminal wires 38, and the ends of heating units in position. 80

Each heating unit comprises a strip of non-conducting material 39, as mica, and wound around said strip is a resistance coil 40 that has the end convolutions thereof terminating beyond the ends of the mica strip. Inclosing the ends of the mica strip and the ends of the resistance coil are binding pieces 41 apertured as at 42 to receive the shanks 33 of the terminals 34. Inclosing the mica strip 39, the resistance coil 40 and the inner ends of the binding pieces 41, is a casing 43, preferably of mica. Surrounding the ends of the mica casing 43 are short flexible armor sleeves 44 and connecting said flexible armor sleeves is a rigid armor 45. 95

The supports 24 and 25 are elevated relative to the front and rear rails 55 in order to support the units in a plane above the grid plate 18 and in consequence of this arrangement it is necessary to make the sleeve 44 of flexible material in order that the ends of each unit can be bent downwardly toward the terminals 34. The downwardly bent sleeves 44 tend to deflect liquid and to prevent liquid from passing on to the binding pieces 41, the outer ends of the sleeves 44 are enlarged to accommodate a non-conducting cement 46 upon the upper side of the casing 43. Gutters 47 are thus formed at the ends of each unit to carry off any liquid that tends to flow toward the outer ends of the sleeves 44. A similar cement is also placed at the juncture of the sleeve 44 and the armor 45 to prevent moisture from entering the ends of the armor, and the unit in its entirety is positively protected from the action of moisture. 110

The heating units are arranged in parallelism, as best shown in Fig. 11 and tapped into the support 25 are screws 48, the heads of which overlie the edges of the units intermediate the ends thereof, and prevent buckling or distortion. The flexible downwardly bent ends of the units permit for expansion and contraction, and should the usefulness of a unit be impaired, it is an extremely easy matter to remove the injured unit without disturbing the other unit. 120 125

To protect the terminals 34 and the binding pieces 41 from the effects of liquid or 130

other foreign matter, hoods or covers 49 are employed. These hoods have deflecting surfaces 50 and 51, the latter in the form of a gutter having drain spouts 52 between the heating units whereby liquid or other matter deposited upon the hood will drain into the drip pans 20. The hoods or covers are held between studs or pins 53 at the ends of the side bars 23 and said side bars are supported on the ledge 17 and prevented from becoming accidentally displaced by positioning pins or lugs 54 engaging in openings provided therefor in the ledge.

In the range casing, below the cooking top 15 and contiguous to the front wall 5, is a terminal box including novel conduits and indicating devices. The terminal box is a bench-made proposition, that is, the various devices and structural elements entering into 20 the make up of the terminal box are assembled prior to being placed in the range casing, consequently the terminal box can be bodily handled and its installation quickly 25 accomplished. With this same end in view, certain conduits are integral with a switch plate and disposed so that easy access can be had to the same. The conduits are 30 designed to deflect and shed liquid and thereby protect electrical connections in said conduits.

The front wall 5 of the range casing has an oblong opening 56 and secured to the inner side of said wall, as at 57 are the apertured lugs 58 of a switch plate 59. The 35 upper part of the switch plate is formed with a plurality of pockets 60 and communicating with the outer ends of said pockets are switches 61 connected to the plate 59 by screw bolts 62. The inner ends of the pockets 60 are in communication with conduits generally designated 63, 64, 65 and 66. Each conduit comprises a channel member 67 and a cover 68, said cover projecting beyond the edges of the channel member to 40 prevent liquid from entering said member. The channel members of the conduits 63, 64 and 65 are integral with a connecting bar 69, which is secured to the inner side of the switch plate 59, as at 170. The conduits 63, 50 64 and 65 converge and are integral with a central conduit 70 having for its lid or cover the transverse terminal member 22. The central conduit 70 has a branch 71 in communication with one of the pockets 60, said 55 branch conduit having a detachable lid or cover 72, which also forms an end of the central conduit 70. This is best shown in Fig. 8.

The terminal member 22 is provided with 60 openings 73 communicating with openings in blocks 74 secured to the member 22, said blocks being made of porcelain or other insulation material. The terminal wires 38 extend through the blocks of insulation 74 65 into the central conduit 70 and to their re-

spective switches through the medium of the conduits 63, 64, 65 and 71. The central conduit 70 has an opening 75 intermediate the ends thereof and this opening communicates with a transverse conduit 76 secured to 70 and supported by the central conduit 70. The transverse conduit 76, for the greater part of its length, is an inverted channel member that sheds liquid from terminal wires 77 connecting the outer sides of the 75 heating elements and switches 61.

The switches 61 are of a conventional form, preferably the rotary type, having a plurality of contacts 78, a central spindle 79, and spring actuated blades 80 adapted to 80 engage the contacts 78 and establish independent circuits. In order that this type of switch can be conveniently used in connection with the range, it is necessary to prolong the spindle 79 of the switch and this 85 is accomplished by placing a member 81 in screw threaded engagement with the spindle. A split washer 82 is clamped between the spindle 79 and the member 81 to rotate therewith and said split washer has an arm 90 83 extending into a recess 84 of an indicating member 85 loosely mounted upon the member 81. The indicating member 85 is cylindrical and extends through an opening 86 in a stationary dial plate 87 secured over 95 the upper part of the opening 56 of the front wall 5. The stationary dial plate 87 is preferably connected to apertured lugs 88 of the switch plate 59, and the walls of the opening 86 are adapted to brace the indicating member 85 should the member 81 be subjected to stresses and strains or an accidental blow. The outer end of the member 85 has a pointer or indicator 89 movable in front of the dial plate 87, and said plate is 100 embossed or marked with such designations as "Off," "Full," "Medium (Med.)," "Low," said designations corresponding to the four contacts of the rotary switch.

An operating button 90 is mounted upon 110 the outer end of the member 81 whereby a rotary movement can be imparted to the spindle 79 and as said spindle is rotated, the arm 83 of the washer 82 imparts movement to the indicating member 85. Simultaneous 115 with this operation, a spring 91 connected to the washer 82 is placed under tension. When the spindle 79 has been rotated a quarter of a revolution, and the pointer or indicator 89 positioned at one of the designations of the dial plate 87, then the tension of the spring 91 is released and said spring shifts the blades 80 of the switch. It is therefore apparent that the pointer or indicator 89 moves in advance of an actuation 120 of the blades 80, it being possible to place the pointer indicator at a designation before the switch snaps and completes or breaks a desired circuit. It is therefore apparent that an operator of the range must swing the 125

pointer 89 to a desired position before the switch is actually operated, consequently a movement of the pointer must be fully determined and actually accomplished before there is a change in heat. With the pointer 89 large and of a decided color, as black, against the nickel plated and highly polished surface of the dial plate 87, the position of the pointer can be readily observed from a distance and should the operator of the switch inadvertently turn the button 90 counter clockwise, the button or the member 81 will unscrew and thereby prevent possible injury to the switch.

15 Associated with the stationary dial plate 87 is a hinged dial plate 92, carried by the front wall 5. This dial plate closes the remainder of the opening 56 and is provided with such designations as "left back," "right back," "left front" and "right front," these designations being associated with the heating elements of the cooking top; also "baking" and "broiler," associated with heating elements of the main oven of the range.

20 25 The hinged plate 92 is retained in a closed position by a turn button 93 or suitable fastening means, and said plate is hinged whereby easy access can be had to the lower part of the switch plate 59, which is provided with a plurality of plug fuse blocks 94, one for each switch. The fuse blocks 94 have connections 95 with the switches 61 and one of said fuse blocks has connections 96 with a socket 97, carried by the front wall 30 35 5 of the range. This socket permits of an electrical connection for operating electrical devices, for instance, an electric iron.

Connected to the plug fuse blocks 94 are bus bars 98 connected to a cartridge fuse 40 45 block 99, carried by a transverse wall 100 supported by the switch plate 59. Service wires to the cartridge fuse block 99 can enter the range casing at any desirable point, preferably through the bottom plate 1 contiguous to the wall 100.

By reference to Figs. 7 and 8, it will be observed that the accessories of the terminal box are snugly and compactly arranged and that the switch plate 59 is designed whereby 50 55 positive electrical connections can be made between the switches, the heating elements and the fuse blocks. A portion of the switch plate 59 is off-set in order that the switches 61 controlling the baking and broiler circuits can be of larger size than the remainder of the switches, since the heating elements of the oven, to be hereinafter described require a greater voltage than the heating elements of the cooking top.

60 65 In the oven housing is an inner shell or oven proper that is spaced from the rear, side, top and bottom walls of the housing and comprises side walls 101 and 102, a rear wall 103 and top and bottom walls 104 and 105 respectively. These walls are compara-

tively thick relative to the housing walls and form a rectangular compartment in communication with a doorway 106 in the front wall 12. The walls 101 to 105 inclusive are made of cast aluminum, which possesses 70 characteristics indispensable in an oven heated by electricity. In the first place, cast aluminum of considerable thickness will hold more heat than any common metal and to melt it, aluminum absorbs as much heat 75 as cast iron, though its melting point by a pyrometer is only 1100. On account of the high specific heat of aluminum, the walls of the oven absorb heat and maintain a uniform temperature throughout the oven. The 80 molecular composition of the metal is such that each crystal has mirror like or reflecting facets and as air is excluded, the crystals reflect heat, particularly after a desired temperature has been reached, and it is through 85 the medium of such metallic walls that the temperature within the oven can be quickly raised and maintained by electrical elements employed for such purpose. By providing an air space between the oven housing and the oven proper the heating elements 90 first heat the oven walls proper and then the air in the space surrounding said walls, and it is unnecessary to use asbestos or a non-conductor of heat, and by 95 eliminating packing there is a material reduction in the weight and greater facility in assembling. Furthermore, the inner sides of cast aluminum walls, after a few days use in connection with an oven become coated or 100 stained a dark brown or black and provide a good heat absorbing and radiating surface, while the outer sides of the walls retain the original luster and retard heat radiation. It is therefore apparent that an aluminum 105 walled oven has a capacity of storing heat that is new and useful, and as the heat is given back into the oven without radiating from the outer walls thereof, the temperature 110 of the oven can be quickly raised and maintained. The air space surrounding the oven is chambered by a horizontally disposed partition 107 mounted upon a flange 108 of the top wall 104. This partition prevents an unequal distribution of hot air 115 around the oven particularly at the top thereof, and said partition assist in properly spacing the oven proper relative to the housing. The side walls 101 and 102 of the oven are provided with spacing lugs 109 connected to the walls 7 and 9 of the housing by 120 screws or other fastening means.

The inner sides of the walls 101 and 102 are provided with grid supports or brackets 110 and the edges of the walls 101, 102, 104 and 105 are connected to the front wall 12.

Closing the doorway 106 is a hinged door 111 having a spaced lining 112 made of aluminum, said lining coöperating with the 125 walls of the oven in maintaining a baking 130

temperature within the oven with a minimum expenditure of current.

Hinged or trunnioned in the upper part of the oven is a broiler heating element generally designated 113 that is maintained normally in parallelism with the top wall 104 of the oven by a button or catch 114 that can be laterally shifted to release the free edge of the heating element, whereby said heating element can be swung into or through the doorway 106 for repair purposes or for utilizing the heating element as a toaster.

Hinged or trunnioned in the lower part of the oven, adjacent the rear wall 103, is an oven heating element generally designated 115. This element rests normally upon the bottom wall 105 of the oven, but can be raised for repair purposes or when it is desired to cleanse the oven. The broiler and oven heating elements are identical in construction, with the exception that the broiler heating element is of a less length than the oven heating element, which is necessary in order that the broiler heating element can be swung clear of the oven heating element.

Reference will now be had to Figs. 16 to 21 inclusive showing the detail construction of either of the heating elements. A rectangular frame having channel side bars 116, a channel rear bar 117 and a solid front bar 118 supports spaced parallel heating units 119. The general make up of the heating units 119 is similar to the units of the heating elements forming the cooking top of the range. The heating units 119 rest upon a brace 120 connecting the rear bar 117 and the solid bar 118, said units being retained in engagement with the brace by turn buttons 121. The turn buttons 121 prevent the units 119 from buckling and the ends of said units are connected to terminals 122 in the channel side bars 116. The terminals 122 are constructed upon the same principle as the terminals 34 of the cooking top heating elements, and said terminals are supported by longitudinal strips 123 mounted upon transverse ribs 124 within the channel side bars 116. The strips 123 are secured to some of the ribs 124 by screws 125 or other fastening means. Bridge pieces 126 connect said terminals and said bridge pieces are disposed whereby leading in wires 127 can be connected to the terminals 122 in one of the channel side bars 116.

The side bars 116 are provided with covers 128 and the rear bar 117 with a cover 129, the ends of which overlap the ends of the covers 128. The inner edges of the covers 128 are provided with extensions 130 for the ends of the heating units 119, and all of said covers and the extensions thereof are shaped to deflect and shed liquid or foreign matter that might be deposited upon the heating element. The covers 128 and 129 are retained in position by swiveled clamps or

buttons 131 and 132, the former being on the front bar 118 and the latter upon webs or corner pieces 133 at the juncture of the side and rear bars 116 and 117.

One end of the rear bar 117 has a solid trunnion or pivot pin 134 and the opposite end of said bar has a hollow trunnion or pivot pin 135 through which extends the leading in wires 127. The trunnions 134 and 135 extend into porcelain bushings or bearings 136 at the juncture of the walls 104 and 103 with the walls 101 and 102. (See Fig. 3).

The leading in wires 127 of the heating element 113 extend into a junction or receptacle box 137 connected to the wall 9 of the oven housing, said junction box having a detachable cover 138. The junction box 137 is in communication with the conduit 139 that extends through the partition 11. The leading in wires within the conduit 139 extend into a pocket 60 of the switch plate 59 and are connected to the switch 61, which controls the broiler heating element.

The leading in wires of the heating element 115 extend into a junction or receptacle box 140 and from said junction box into the conduit 66 and to the switch 61 controlling the operation of the oven heating element.

In the warming oven is a heating element comprising two units 141 connected by wires 142 to one of the fuse blocks 94 and to an ordinary knife switch 143. The knife switch 143 is mounted upon a bracket or an extension 144 of the switch plate 79, and the knife of said switch extends through an opening and an escutcheon plate 145 of the front wall 5. The warming oven has a hinged door 146 and it is through the medium of this door and the hinged partition 13 that access is had to the cartridge fuse block 99. A grid 147 is detachably mounted in the warming oven above the heating element thereof.

As an instance of the operation of the electric range, see Figs. 2 and 22. The switch for the right back heating element of the cooking top is shown as swung on full and the live circuit is indicated by a heavy line and the direction of current indicated by arrows. The switches for the left front and right front are shown as swung to medium and low. The circuits are indicated in connection with Fig. 22, also the complete wiring of the electric range, and it is thought these circuits will be clearly understood without entering into a detailed description of the same.

What I claim is:—

1. In an electric range, a heating top, heating elements in said heating top, a terminal box below said top and having electrical connections with all of said heating elements, said terminal box being bodily removable

- from said heating top, and indicating devices in front of said terminal box for predetermining the operation of said heating elements.
5. 2. In an electric range, a heating top, a main oven, a warming oven, heating elements in said ovens and said heating top, a unitary terminal box for said heating elements and having closed conduits extending 10 in the direction of said heating elements, and indicating devices in front of said terminal box for predetermining the operation of said heating elements.
15. 3. In an electric range, a casing having a heating top, heating elements in the heating top of said casing, a terminal box in said casing below said heating elements, said terminal box being bodily removable from said casing and comprising a switch plate, 20 switches carried thereby, a transverse member, liquid shedding conduits connecting said plate and said member, and wires in said conduits connecting said switches and said heating elements.
25. 4. In an electric range, the combination with a plurality of heating elements, of a unitary terminal box detachably mounted in said range and bodily removable therefrom, said terminal box including grouped liquid shedding conduits extending in the direction of said heating elements.
30. 5. In an electric range, the combination with a casing and a plurality of heating elements, of a unitary terminal box detachably mounted in said casing and bodily removable therefrom, said terminal box including switches, liquid shedding conduits extending from said switches in the direction of said heating elements, and indicating devices for predetermining the operation of said switches.
35. 6. In an electric range, a casing, an oven housing supported thereby, trunnioned broiler and oven heating elements in said housing, and a unitary terminal box detachably mounted in said casing and bodily removable therefrom and including switches and liquid shedding conduits containing wires extending from said switches to said heating elements.
40. 7. In an electric range, a casing, superimposed ovens, heating elements in said ovens, a unitary terminal box in said casing and bodily removable therefrom, said terminal box including switches, liquid shedding conduits containing wires leading from said switches to said heating elements, and indicating devices for predetermining the operation of said switches.
45. 8. In an electric range, a casing, a dial plate carried thereby, a unitary terminal box in the rear of said dial plate and bodily removable from said casing, switches forming part of said terminal box, and indicating devices operatable in front of said dial plate and connected to said switches.
50. 9. In an electric range, a heating top, heating elements in said heating top, and a terminal box below said top and having electrical connections with all of said heating elements, said terminal box being bodily removable from said heating top. 70
55. 10. In an electric range, the combination with a plurality of heating elements, of a unitary terminal box detachably mounted in said range and bodily removable therefrom, 75 said terminal box including channel conduits extending in the direction of said heating units, and covers on said channel conduits having overhanging edges to prevent liquid from entering said conduits.
60. 11. The combination with an oven housing, of an aluminum oven therein with the walls of said oven spaced from the walls of said housing, trunnioned heating elements 80 in parallelism and at the top and bottom walls of said aluminum oven, and conduits and junction boxes in said oven structure adapted to house wires leading to said elements. 90
65. 12. The combination with an oven housing, of an oven having the walls spaced from the walls of said housing and in communication with a doorway of said housing, an electric heating element trunnioned in said oven and resting normally upon the bottom thereof and capable of being raised at the front and swung toward the back of the oven, and an electric heating element trunnioned at the top of said oven and capable 95 of being swung downward toward the doorway of said oven. 100
70. 13. In an electric range, an oven housing, an oven therein and spaced from the walls of said housing, a horizontal partition at the top of said oven connected to the walls of said housing, an electric heating unit upon the bottom of said oven, and a broiler heating unit trunnioned at the top of said oven and normally maintained in parallelism therewith. 110
75. 14. The combination with an oven, of the heating elements therefor, comprising a rectangular frame composed of covered end and back troughs, trunnions at the ends of the back trough of said frame, one of which is hollow to communicate with an opening in the side of said oven, and leading in wires extending through the hollow trunnion into the back trough of said frame. 115
80. 15. In an electric range, a heating top, heating elements forming part thereof, each element comprising rigid armors located above the surface of said heating top, and flexible armors at the ends of said rigid armors bent downwardly beneath said top and then upwardly to deflect liquid sidewise from the ends of said units. 120
85. 16. In an electric range, a heating top, heating elements forming part thereof, each element comprising rigid armors located above the surface of said heating top, and flexible armors at the ends of said rigid armors bent downwardly beneath said top and then upwardly to deflect liquid sidewise from the ends of said units. 125

16. In a range, an oven electrically heated from within and having a door side, a tight shell surrounding said oven on all sides except the door side and providing an air chamber between said shell and the oven wall and a division plate dividing said air chamber into two air spaces, one comprising the space above the oven top and the other

comprising the space below the oven body and around the sides of the oven. 10

In testimony whereof I affix my signature in presence of two witnesses.

WILLIAM J. KEEP.
